United States Patent Office

Des. 175,324
Patented Aug. 9, 1955

175,324

REAR WINDOW VISOR FOR AUTOMOBILES

James T. Sullivan, Kansas City, Mo.

Application June 29, 1953, Serial No. 25,709

Term of patent 3½ years

(Cl. D14—6)

Fig. 1

Fig. 2

Fig. 3

INVENTOR.

James T. Sullivan
BY

Fig. 1 is a rear elevational view of a visor embodying my new design,

Fig. 2 is a side elevational view thereof, and

Fig. 3 is an enlarged sectional view taken on line III-III of Fig. 1.

The fragmentary portion of the automobile disclosed by means of dotted lines is shown only for the purpose of illustration.

I claim:

The ornamental design for a rear window visor for automobiles, as shown and described.
